[57] CLAIM

The ornamental design for a container, as shown.

DESCRIPTION

FIG. 1 is a front elevational view of a container, showing my new design;

FIG. 2 is a top plan view thereof;

FIG. 3 is a right side elevational view thereof;

FIG. 4 is a bottom plan view thereof;

FIG. 5 is a bottom plan view of the lid of the container shown in FIG. 1;

FIG. 6 is a side elevational view thereof;

FIG. 7 is an end elevational view thereof;

FIG. 8 is a top plan view thereof;

FIG. 9 is a top front right side exploded perspective view of the container and lid;

FIG. 10 is a top front right side perspective view thereof with the container shown in a closed position;

FIG. 11 is a rear elevational view of that shown in FIG. 1; and

FIG. 12 is a left side elevational view thereof.
